COMBINED DOUBLING AND TWISTING
MACHINEJoseph P. McHugh, Pawtucket, R. I., assignor, by
mesne assignments, to Industrial Machine Cor-
poration, a corporation of DelawareApplication April 19, 1937, Serial No. 137,879
Renewed March 12, 1940

21 Claims. (Cl. 57—75)

This invention relates to new and useful improvements in combined doubling and twisting machines and deals more particularly with modifications applicable to conventional down ring spinning machines of the so-called 5B type, which will adapt said machines to the production of finished lustrous yarn packages.

The primary object of this invention is to provide a machine of the above-mentioned type in which the several spindles and their associated stop motion mechanism are divided into a plurality of groups, with any desired number of spindles in a group, so that the building of the packages and the stopping of the spindles, as a result of breakage of single ends or completion of packages, may be effected by mechanism individual to each group.

A further important object of the invention is to provide traverse or builder motion mechanism of such character that the formation of packages on a small number of spindles, controlled as a group, may be interrupted at any point in the building thereof and again resumed at a later time without affecting the final contour of the interrupted packages and without interfering with the continuity in the production of any of the remaining packages of the machine.

A further important object of the invention is to provide traverse or builder motion mechanism of such character that the ring spinners for all of the spindles of a machine will partake of traverse strokes of the same amplitude while the package building movements of the ring spinners will be effected by mechanism which is duplicated in accordance with any desired grouping of the several spindles.

Another object of the invention is to provide stop motion mechanism for a machine of the above-mentioned type which will operate to stop the several spindles of a correlated group, which forms only a small portion of the total number of spindles in the machine, either upon the breakage of any single end going to any of the spindles in said group or upon completion of the building of packages on the spindles of the group.

Other objects and advantages of the invention will be apparent during the course of the following description.

In the accompanying drawings, forming a part of this specification and in which like numerals are employed to designate like parts throughout the same,

55 Figure 1 is a fragmentary side elevational

view, showing the improvement of the present invention applied to a conventional 5B doubling and spinning frame,

Figure 2 is a transverse sectional view illustrating the manner of application and operation of the said invention as applied to spindles at opposite sides of the spinning frame,

Figure 3 is a fragmentary plan view illustrating the arrangement of correlated groups of spinner rings arranged on opposite sides of the frame with the individual builder motion mechanism for each group of spinner rings,

Figure 4 is a fragmentary top plan view of the thread guides associated with a correlated group of spindles and their ring spinners and illustrates the manner in which the thread guides for the several spindles of the group are operatively interconnected to individually control stop motion mechanism for the several spindles of a group,

Figure 5 is a detail, fragmentary side elevational view illustrating the builder motion mechanism for one group of spindles,

Figure 6 is a detail, side elevational view showing a portion of the mechanism illustrated in Fig. 5,

Figure 7 is a detail, fragmentary sectional view of a portion of the builder motion mechanism illustrated in Fig. 5, and

Figure 8 is a detail plan view illustrating a modified form of group control builder motion mechanism.

The invention now will be described in connection with the drawings illustrating an exemplary adaptation thereof to a conventional 5B doubling and spinning frame. The essential portions of the 5B machine which have been retained without modification first will be referred to briefly.

Referring particularly to Figs. 1 and 2, the reference character A designates in its entirety the frame portion of the machine which has the usual overhead creel structure B properly mounted thereon. A spindle supporting rail extends longitudinally of the machine and supports the two parallel rows of swing spindles D. The spindles are adapted to be driven by the conventional, continuous belt E and relative to which the spindles are swung into and out of driving relation by the action of the spring pressed stop motion rod F. A ring rail G extends longitudinally along each side of the machine. Both of these ring rails are adapted to partake of a predetermined, uniform vertical reciprocating motion imparted thereto by a con-

- ventional heart cam traverse mechanism which is designated in its entirety by the reference character H, as best shown in Fig. 1. The traverse mechanism H is driven from the feed roll drive shaft J in the conventional manner, as illustrated in Fig. 1. Feed roll mechanism for delivering the single ends from the creels B to the spindles D is illustrated and designated by the reference character K.
- 5 The parts thus far referred to are entirely conventional and form no part of the present invention, except as the action or operation of the same is affected or modified by the adaptation of the present invention thereto.
- 10 The present invention modifies the normal mode of operation of a conventional 5B doubling and spinning frame to the extent that it divides the spindles and their associated instrumentalities into a plurality of independent 15 groups, with any desired number of spindles to a group, and effects a control over the spindles, their associated spinner rings, feed rolls and stop motion devices, so that the action of each group of spindles will be independently controlled with 20 the result that final packages may be wound on the several spindles by means of a single cycle form of wind, and the formation of packages on the spindles of any group may be interrupted at 25 any time in the building thereof and again resumed at a later time without affecting the final 30 contour of the interrupted packages and without interfering with the continuity in the production of any of the remaining packages of the machine.
- 35 In Fig. 3, three spinner rings 10 are illustrated as being interconnected and supported by a ring bar 11 by means of the lateral flanges 12 of the rings being adjustably fastened to the lateral arms 13 which form a part of the ring bar 11.
- 40 This ring bar couples the three rings together to cause these rings to constitute a group. It is to be understood that any desired number of rings may be coupled together to form a group. All of the groups of rings are intended to 45 partake of the uniform, vertical reciprocatory movement of the ring rails G to effect the traverse movement of the rings relative to the spindles D. The building of the packages by advancing the traverse movement of the rings longitudinally of 50 the spindles is effected, however, by builder motion mechanism which is carried by the ring rails and is provided one such mechanism for each group of spinner rings. This individual group builder motion mechanism will effect relative 55 movement of the rings 10 with respect to their associated ring rail G. For the purpose of providing stability for the rings, each one of the rings is provided with a laterally projecting bifurcated finger 14 which receives between its furcations a perpendicular guide rod 15 mounted on the ring rail G.
- 60 The individual group builder motion mechanism will be described in detail in connection with Figs. 2, 3 and 5 to 7 inclusive. The ring rails G have mounted thereon one reversely bent angle bracket 16 for each individual group builder motion mechanism. Each angle bracket 16 has formed at its inner end an upstanding arm 17 carrying a bearing stud 18 on which is pivotally 65 mounted a pawl carrying lever 19, see Figs. 5 and 6, which lever in turn carries a pivot bearing 20 for the pawl 21. Coiled around the bearing stud 18 is a coil spring 22 which functions to lift the lever 19 and return the pawl 21 to the starting 70 point of its stroke, after actuation, to permit the

pawl to reengage one of the teeth 23 on the ratchet wheel 24.

By inspecting Figs. 2 and 5, it will be seen that the ratchet wheel 24 is provided with a hub 25 of tubular formation and adapted to rotatably engage the upper face of the angle bracket 16. Axially aligned with the hub 25, the angle bracket 16 is provided with a downwardly extending bushing 26 which is apertured to loosely receive the threaded rod 27. The bore of the wheel hub 25 is smooth or unthreaded, and movably receives within an opening 28, formed in its side wall, a knife blade thread providing element 29 which is pivoted to the hub 30 and is retained in its threaded bar engaging position by means of the 15 spring 31, see Fig. 7. It will be appreciated that this knife blade element 29 acts as a thread connection between the hub 29 and the threaded bar 27 and this thread connection may be severed or broken when desired by merely pivoting the blade element 29 about its pivot 30, against the tension of the spring 31. This severance of the threaded connection between the wheel hub 25 and the threaded bar 27 will permit the ratchet wheel 24 and its hub 25 to be 20 moved manually along the length of the rod and vertically with respect to the angle bracket 16 which is carried by the ring rail G. Such a manual and rapid manipulation of the ratchet wheel 24 relative to the bracket 16 and the ring 25 rail will facilitate doffing of the packages which have been formed on the spindles associated with the group of spinner rings controlled by the builder motion mechanism being described. This 30 action will be more apparent as the description 35 of this builder motion mechanism proceeds.

It thus will be seen that rotation of the ratchet wheel 24, effected through the medium of the pawl 21, will function to advance the rod 27 vertically through the angle bracket 16 and the hub 25 of the ratchet wheel 24. It will be observed, however, that the bracket 16, ratchet wheel 24, and pawl 21 with its actuating lever 19 are all carried by the ring rail G, and that these elements jointly partake of the uniform 45 vertical or reciprocatory motion imparted thereto so that the movement of the threaded bar 27, together with the elements carried thereby, is superimposed upon the movement of the ring rail G.

The pawl actuating lever 19 is adapted, when the ring rail G reaches the upper limit of its stroke, to contact the lower face of the cam 32 and to be moved, by this engagement, about the pivot 18 to cause the pawl 21 to advance the 55 ratchet 24 a predetermined distance. It is apparent that the distance of movement of the ratchet wheel 24, effected by the pawl 21, is dependent upon the magnitude of the movement of the free end of the pawl carrying lever 19 and that the latter movement is dependent upon the position of the cam 32. This cam 32 is carried on the stop motion rod F, see particularly Figs. 5 and 6, through the medium of the collar 33, which is adapted to be locked in any desired position 60 of adjustment by means of the set screw 34. The collar 33 carries the bearing pin 35 on which the cam 32 is mounted. This cam 32 has formed integrally therewith a ratchet 36 while a pawl carrying member 37 is fixedly mounted upon the 65 bearing pin 35 and carries the pawl 38. The ratchet 36 and pawl 38 function to hold the cam 32 in any particular position to which it may be lifted. The cam 32 is adapted to control the initial winding of the cone on the spindle and is 70 75

adapted to be actuated for this purpose through the medium of the arm 39.

Returning now to the threaded rod 27, it already has been observed that this rod is adapted to partake of two movements: first, the uniform reciprocatory movement of the ring rail G and, second, the step-by-step vertical movement imparted thereto by actuation of the ratchet wheel 24. The rod 27 has clamped thereon a ring supporting bracket or collar 40, held in position on the rod 27 by a set screw 41. This bracket or collar 40 is formed integrally with the ring bar 11 and cooperates with the ring bar 11 and branch arms 13 for locating the various rings 10, connected to the arms 13 over the ring rail G and in coaxial alignment with the associated spindles D. As clearly shown in Fig. 5, the ring 10 is provided with a conventional traveler 42.

The threaded rod 27 additionally carries a collar 43 which is located above the point of attachment thereto of the bracket 40 and is adjustably secured to the rod 27 by means of the set screw 44. This collar carries the L-shaped arm 45, see particularly Figs. 2, 3 and 5, which is adapted, on the upward stroke of the ring rail G during the initial building of a cone, to contact the arm 39 and impart thereto a slight movement to effect turning of the cam 32 about the bearing pin 35. The configuration of the cam 32 and the manner of its actuation through the medium of the arms 39 and 45 control the building of the base of the cone on a spindle. The building of a small base cone at the bottom of the spindle is accomplished in accordance with the present invention by so correlating the configuration of the cam 32 and the action of the pawl 21 on the ratchet wheel 24 that, during the initial building of the cone, the spinner ring 10 is advanced vertically of the spindle in a step-by-step movement of progressively decreasing extent.

The vertical displacement of the ring 10 with respect to the ring rail G, effected by each contact of the pawl actuating lever 19 with the cam 32, diminishes until the cam 32 and the arm 39 have been turned until the position occupied by the right hand cam in Fig. 2 is obtained. In this position, the cam arm 39 is completely out of the path of movement of the actuating arm 45, carried by the pivot rod 27, and accordingly the cam 32 remains stationary. The arm of the cam 32 remains stationary and the throw of the pawl 21 then is constant, causing the threaded rod 27, carrying the ring 10, to thereafter advance at a uniform rate during the building of the remainder of the cone. It will be observed that the pivot bearing 18 for the pawl actuating lever 19 and the pivot bearing 35 for the cam 32 occupy, throughout the operation of the builder motion, a predetermined uniform relationship and that the throw of the pawl 21 is controlled entirely by the position of the cam 32.

In Figs. 1, 2 and 3, the stop motion rods F which are associated with the three spindles D and the spinner rings 10 which are interconnected to operate in a group by one ring bar 11, are all interconnected to likewise operate as a group by means of a horizontally extending bar 46 which is connected to the three stop motion rods F by the coupling members 47. The stop motion rod F for the middle spindle of the group carries the cam 32 and its associated elements. As clearly shown in Fig. 3, the builder motion mechanism, most completely illustrated in Fig. 5, is associated with the ring bar 11 so that it will cooperate with

the cam 32 carried by the center stop motion rod F. It has been pointed out heretofore that the cam 32 is carried by a stop motion rod F. This is particularly advantageous for the reason that when any one of the three stop motion rods, 5 coupled by a horizontal rod 46, is released and elevated, in a manner to be explained at a later point, it carries with it the remaining two stop motion rods and particularly the rod F which has mounted thereon the cam 32. This cam, 10 therefore, is elevated completely above the upper limit of movement of pawl actuating lever 19 so that when the stop motion rods are raised, no further actuation of the pawl 21 and ratchet wheel 24 occurs. Accordingly, adjustment of the 15 three rings 10, actuated as a group by the particular builder motion mechanism under consideration, relative to the ring rail G is stopped until the three affected stop motion rods are restored to their normal operative position. As soon as 20 the three affected stop motion rods are returned to their normal positions, the cam 32 is again rendered effective to actuate the pawl carrying lever 19 and thereby again causes a step-by-step 25 vertical movement of the threaded rod 24 and its 25 associated three spinner rings 10.

It is thus apparent that if the formation of any group of packages is interrupted at any time during the building thereof, such formation again can be resumed without in any way affecting the 30 contour of the group of final packages since, during the period that the building is interrupted, the three rings of the stopped spindles do not change their positions with reference to the 35 length of the packages. The fact that an individual builder motion is provided for each interconnected group of spindles, therefore, makes it possible to interrupt the building of the packages on the group of spindles without in any way 40 affecting the ultimate contour of these interrupted packages or without interfering in any way with the continued building of the packages on any of the remaining spindles of the machine. It will be apparent, therefore, that the various 45 groups of spindles may at any time have packages being built thereon which are at many different stages of development as the building of each group of packages is entirely independent of any of the remaining groups.

The stop motion rods F, with the exception of 50 being interconnected to operate in groups, function in response to the breakage of any single end coming from the supply spools on the creel B. This group operation of the stop motion rods now will be explained:

Referring particularly to Figs. 2 and 4, it will be seen that the conventional thread guide or drops 48 are provided in suitable numbers for each one of the spindles. These various thread guides are all pivoted at 49 and are normally retained in the position illustrated in Fig. 2 when unbroken single ends are feeding through the same to the various ring spinners. Upon the breakage of any single end, its thread guide or drop 48 is permitted to swing inwardly for lowering its end 50. This downward movement of the end 50 actuates a latch release member 51, through the medium of a horizontally extending rod 52 which extends the full width of the several thread guides 48 cooperating with the spindle to 70 which the broken single end was being fed. Actuation of the latch release member 51 causes pivotal movement of the same about the pivot 53 for moving the inner end of the member 51 into the path of movement of the rockably actuated cam 75

arm 54 which is constantly driven from the source of power employed for driving the entire machine. When the inner end of the latch release member 51 is engaged by the rocking cam 54, the member 51 is moved longitudinally and results in pivoting of the latch 55 to the lower end of which the member 51 is pivotally connected. Fig. 4 discloses the fact that all of the latch members 55 for an interconnected group of spindles and their associated devices, are interconnected to operate in unison by means of the longitudinally extending rod 56 to which all of the latch members 55 are rigidly attached. Each latch member 55 is adapted normally to engage the hooked end of an arm 57 which is carried by the upper end of its associated stop motion rod F. It now will be seen that when any thread guide or drop 48 is released by the breaking of its single end, all of the latch members 55, which are interconnected by a rod 56, will be actuated and the stop motion rods F associated with the actuated latch members 55 will be released. The conventional springs, provided for all of the stop motion rods F which have been released will cause these released rods to move upwardly for braking the drives to the feed rolls K and for shifting the spindles D out of driving relation with the belt E and into engagement with braking devices for the spindles in the manner conventional for a 5B machine.

By considering Figs. 1, 2 and 3, it will be seen that each one of the threaded rods 27 is provided at its upper end with a laterally extending arm 58 which is moved into engagement with the lower end of a stop motion release rod 49 when any one of the rods 27 has been moved sufficiently to carry its three associated spinner rings 10 to the level of the upper ends of the packages which are being built on the associated spindles D. This engagement between the arms 58 and the associated rods 59 cause these rods to move upwardly until they engage the inner ends of the associated members 51. These members 51 are then caused to move into the path of the cams 54 with the result that the members 51 are actuated to trip their latch members 55. The interconnected stop motion rods F then will be permitted to move upwardly for stopping the building of packages on the associated spindles D. This action takes place when the packages have been completely built on these spindles.

Fig. 1 discloses the conventional pedals 60 which are employed for depressing the stop motion rods F and returning the feed rolls K and spindles D to their normal operative positions in the usual manner. In the present modification of the conventional 5B machine, one pedal 60 is employed for each interconnected group of stop motion rods F. The pedal 60, preferably, is operatively connected to the middle stop motion rod of a group.

Fig. 8 discloses a modification in the grouping of spinner rings. In this grouping, five rings 10 are connected by the arms 13a to a ring bar 11a, in the same manner as that described in connection with Figs. 3 and 5.

Due to the large number of rings arranged in a group, two builder motion mechanisms are employed for actuating the ring bar 11a. These step-by-step builder motion mechanisms are connected to the ring bar 11a by means of collars 40a which are attached to the threaded rods 27 of the builder motion mechanisms in the same manner as that described in connection with Fig. 5. The stop motion rods F for these five grouped rings are interconnected by a single rod 46a.

As the step-by-step builder motion mechanisms employed for synchronously operating both ends of the ring bar 11a are identical in construction with the mechanism disclosed in detail in Figs. 3 and 5-7 inclusive, these devices of Fig. 8 will not be described in detail. The same reference numerals employed for indicating like parts in Figs. 3 and 5-7 inclusive will be applied to Fig. 8.

In my application Serial No. 102,574 filed Sept. 25, 1936, I have disclosed a modification of a conventional 5B machine which consists primarily of providing a step-by-step builder motion mechanism for each individual spindle. It will be appreciated that in such a machine one builder motion mechanism must be provided for each spindle of a machine. This not only adds materially to the initial cost of a machine but also increases the maintenance burden. As these individual builder motion devices are carried by the ring rails G, the provision of one builder motion for each spindle adds materially to the load or weight which must be carried by the ring rails.

In the present invention, the number of individual builder motion mechanisms is materially reduced. The modification of the invention disclosed in Figs. 1-7 inclusive requires one builder motion mechanism for each group of three spindles. The form of the invention disclosed in Fig. 8 requires two builder motion devices for each group of five spindles. It will be appreciated that I do not desire to be limited to three spindles to a single builder motion mechanism or five spindles to two builder motion devices. Other groupings and combinations clearly will fall within the invention as disclosed herein.

From the foregoing description, it will be apparent that I have devised a novel improvement that may be applied to conventional multiple down ring spinning machines to convert the same into instrumentalities capable of effecting the individual building of groups of packages in conjunction with group actuating traverse mechanisms. It will be observed additionally that, in accordance with the present invention, each group of packages is under individual control without respect to any of the remaining packages and that the building of any given group of packages may be interrupted without interfering with the continuous building of the remaining packages.

It further is to be noted that I have provided for the building of an individual type of yarn base on each of the spindles arranged in a group regardless of the stage to which the building of packages on any of the other spindles may have progressed and that I additionally provide for the stopping of the spindles of any group and their associated builder motion mechanism upon completion of any individual group of packages.

It is to be understood that the forms of this invention herewith shown and described are to be taken as preferred examples of the same, and that various changes in the shape, size, and arrangement of parts may be resorted to without departing from the spirit of the invention or the scope of the subjoined claims.

Having thus described the invention, I claim:

1. An improved doubling and twisting machine, comprising a multiple down ring spinning frame 70 embracing a ring rail, means for reciprocating the ring rail vertically with respect to the spindles carried by the frame, means for interconnecting the spinner rings for the several spindles in a plurality of independently operable 75

groups with a plurality of rings in each group, and an auxiliary builder motion individual to each group, carried by the ring rail.

2. An improved doubling and twisting machine, comprising a multiple down ring spinning frame embracing a ring rail, means for reciprocating the ring rail vertically with respect to the spindles carried by the frame, means for interconnecting the spinner rings for the several spindles in a plurality of independently operable groups with a plurality of rings in each group, and a plurality of synchronously operating auxiliary builder motion devices operatively connected to each group of rings and the ring rail.

15 3. An improved doubling and twisting machine, comprising a plurality of swing spindles, a group of single end thread guides for each spindle, means individual to each spindle for swinging it into a non-driving position, means for interconnecting the spindle swinging means into a plurality of independently operable groups with a plurality of spindle swinging means in each group, and means for causing operation of all of the spindle swinging means of a group upon breaking 25 age of any single end going to a spindle of said group.

4. An improved doubling and twisting machine comprising a multiple down ring spinning frame embracing a pair of parallel ring rails, a row of spindles for each ring rail carried by the frame, a spinner ring for each spindle, means common to both of said ring rails for reciprocating the same vertically with respect to their spindles, a plurality of auxiliary builder motions spaced 30 along and carried by each ring rail, and means for connecting the spinner rings into independent groups and for connecting each of said groups to one of said auxiliary builder motions.

5. An improved doubling and twisting machine comprising a multiple down ring spinning frame embracing a pair of parallel ring rails, a row of spindles for each ring rail carried by the frame, a spinner ring for each spindle, means common to both of the ring rails for reciprocating the same vertically with respect to their spindles, a plurality of auxiliary builder motions spaced along and carried by the ring rail, means for connecting the spinner rings into independent groups and for connecting each of said groups to one of said auxiliary builder motions, and means associated with each builder motion for stopping the associated spindles when the packages thereon have reached a predetermined size without affecting the continued building of the remaining packages on the machine.

55 6. An improved doubling and twisting machine comprising a multiple down ring spinning frame embracing a pair of parallel ring rails, a row of spindles for each ring rail carried by the frame, a spinner ring for each spindle, means common to both of the ring rails for reciprocating the same vertically with respect to the spindles, a plurality of auxiliary builder motions spaced along and carried by each ring rail, means for connecting the spinner rings into independent groups and for connecting each of said groups to one of said auxiliary builder motions, means associated with each individual builder motion for rendering the same inoperative upon the completion of the packages on the group of spindles associated with said builder motions, said means being operable without contacting the yarn packages which have been completed.

7. An improved doubling and twisting machine comprising a multiple down ring spinning frame

embracing a pair of parallel ring rails, a row of spindles for each ring rail carried by the frame, a spinner ring for each spindle, means common to both of the ring rails for reciprocating the same vertically with respect to their spindles, a plurality of auxiliary builder motions spaced along and carried by each ring rail, means for connecting the spinner rings into independent groups and for connecting each of said groups to one of said auxiliary builder motions, cam means 10 associated with each individual builder motion for controlling and effecting variations in the character of the wind of the packages built on the spindles controlled thereby, and means for rendering the cam associated with each individual builder motion inoperative upon the breaking of a thread supplied to any of the spindles associated with the builder motion controlled by the affected cam and also for rendering the said cam inoperative upon the completion of the 15 building of packages on the spindles associated with the builder motion controlled by said cam.

8. An improved doubling and twisting machine, comprising a multiple down ring spinning frame embracing a ring rail, means for reciprocating the ring rail vertically with respect to the spindles carried by the frame, means for interconnecting the spinner rings for the several spindles in a plurality of independently operable groups with a plurality of rings in each group, 30 a plurality of synchronously operating auxiliary builder motion devices operatively connected to each group of rings and the ring rail, and means associated with each plurality of synchronously operating auxiliary builder motion devices for 35 stopping the associated spindles when the packages thereon have reached a predetermined size without affecting the continued building of the remaining packages on the machine.

9. An improved doubling and twisting machine, comprising a multiple down ring spinning frame embracing a ring rail, means for reciprocating the ring rail vertically with respect to the spindles carried by the frame, means for interconnecting the spinner rings for the several 40 spindles in a plurality of independently operable groups with a plurality of rings in each group, a plurality of synchronously operating auxiliary builder motion devices operatively connected to each group of rings and the ring rail, 45 and stop motion means adapted to render each plurality of synchronously operating auxiliary builder motion devices inoperative without interfering with the action of the means for reciprocating the ring rail.

55 10. An improved doubling and twisting machine, comprising a multiple down ring spinning frame embracing a ring rail, means for reciprocating the ring rail vertically with respect to the spindles carried by the frame, means 60 for interconnecting the spinner rings for the several spindles in a plurality of independently operable groups with a plurality of rings in each group, a plurality of synchronously operating auxiliary builder motion devices operatively connected to each group of rings and the ring rail, 65 and means associated with each plurality of synchronously operating auxiliary builder motion devices for stopping the associated spindles when the packages thereon have reached a predetermined size without affecting the continued building of the remaining packages on the machine, said last mentioned means being operable without contacting the yarn of the packages which have been completed.

11. An improved doubling and twisting machine, comprising a multiple down ring spinning frame embracing a ring rail, means for reciprocating the ring rail vertically with respect to the spindles carried by the frame, means for interconnecting the spinner rings for the several spindles in a plurality of independently operable groups with a plurality of rings in each group, a plurality of synchronously operating auxiliary builder motion devices operatively connected to each group of rings and the ring rail, and each plurality of synchronously operating auxiliary builder motion devices being so constructed and arranged that the building of packages on the spindles of any group may be interrupted and later resumed without affecting the contour of the final packages and without interrupting the continuous building of any of the remaining packages on the machine.
12. An improved doubling and twisting machine, comprising a plurality of swing spindles, means individual to each spindle for swinging it into a non-driving position, a ring rail, means for reciprocating the ring rail vertically with respect to the swing spindles, means for interconnecting the spindle swinging means into a plurality of independently operable groups with a plurality of said means in each group, means for interconnecting the spinner rings into a plurality of independently operable groups with the same number of spinner rings in a group as there are spindle swinging means in a group and with the groupings of the rings and swing spindle means coinciding, an auxiliary builder motion individual to each group of rings carried by the ring rail, and means for causing operation of all of the spindle swinging means of a group upon breakage of any single end going to a spindle of said group.
13. An improved doubling and twisting machine, comprising a plurality of swing spindles, means individual to each spindle for swinging it into a non-driving position, a ring rail, means for reciprocating the ring rail vertically with respect to the swing spindles, means for interconnecting the spindle swinging means into a plurality of independently operable groups with a plurality of spindle swinging means in each group, means for interconnecting the spinner rings into a plurality of independently operable groups with the same number of spinner rings in a group as there are spindle swinging means in a group and with the groupings of the rings and swinging means coinciding, a plurality of synchronously operating auxiliary builder motion devices operatively connected to each group of rings and the ring rail, and means for causing operation of all of the spindle swinging means of a group upon breakage of any single end going to a spindle of said group.
14. An improved doubling and twisting machine, comprising a plurality of swing spindles, means individual to each spindle for swinging it into a non-driving position, a ring rail, means for reciprocating the ring rail vertically with respect to the swing spindles, means for interconnecting the spindle swinging means into a plurality of independently operable groups with a plurality of spindle swinging means in each group, means for interconnecting the spinner rings into a plurality of independently operable groups with the same number of spinner rings in a group as there are spindle swinging means in a group and with the groupings of said rings and swinging means coinciding, an auxiliary builder motion in-
- dividual to each group of rings carried by the ring rail, and means for causing operation of all of the spindle swinging means of a group when the packages on the spindles of that group have reached a predetermined size without affecting the continued building of the remaining packages on the machine.
15. An improved doubling and twisting machine, comprising a plurality of swing spindles, means individual to each spindle for swinging it into a non-driving position, a ring rail, means for reciprocating the ring rail vertically with respect to the swing spindles, means for interconnecting the spindle swinging means into a plurality of independently operable groups with a plurality of spindle swinging means in each group, means for interconnecting the spinner rings into a plurality of independently operable groups with the same number of spinner rings in a group as there are spindle swinging means in a group and with the groupings of said rings and swinging means coinciding, an auxiliary builder motion individual to each group of rings carried by the ring rail, and means for causing operation of all of the spindle swinging means of a group when the packages on the spindles of that group have reached a predetermined size without affecting the continued building of the remaining packages on the machine, said last mentioned means being operable without contacting the yarn of the packages which have been completed.
16. An improved doubling and twisting machine, comprising a plurality of swing spindles, means individual to each spindle for swinging it into a non-driving position, a ring rail, means for reciprocating the ring rail vertically with respect to the swing spindles, means for interconnecting the spindle swinging means into a plurality of independently operable groups with a plurality of spindle swinging means in each group, means for interconnecting the spinner rings into a plurality of independently operable groups with the same number of spinner rings in a group as there are spindle swinging means in a group and with the groupings of said rings and swinging means coinciding, an auxiliary builder motion individual to each group of rings carried by the ring rail, and means for causing operation of all of the spindle swinging means of a group and for rendering the individual builder motion for said group inoperative upon breakage of any single end going to a spindle of said group.
17. An improved doubling and twisting machine, comprising a plurality of swing spindles, means individual to each spindle for swinging it into a non-driving position, a ring rail, means for reciprocating the ring rail vertically with respect to the swing spindles, means for interconnecting the spindle swinging means into a plurality of independently operable groups with a plurality of spindle swinging means in each group, means for interconnecting the spinner rings into a plurality of independently operable groups with the same number of spinner rings in a group as there are spindle swinging means in a group and with the groupings of rings and swing spindle means coinciding, a plurality of synchronously operating auxiliary builder motion devices operatively connected to each group of rings and the ring rail, and means for causing operation of all of the spindle swinging means of a group and for rendering the plurality of synchronously operating auxiliary builder motion devices for said group inoperative upon breakage of any single end going to a spindle of said group.

18. An improved doubling and twisting machine, comprising a plurality of swing spindles, means individual to each spindle for swinging it into a non-driving position, a ring rail, means for reciprocating the ring rail vertically with respect to the swing spindles, means for interconnecting the spindle swinging means into a plurality of independently operable groups with a plurality of spindle swinging means in each group, means for interconnecting the spinner rings into a plurality of independently operable groups with the same number of spinner rings in a group as there are spindle swinging means in a group and with the groupings of rings and spindle swinging means coinciding, an auxiliary builder motion individual to each group of rings carried by the ring rail, and means for causing operation of all of the spindle swinging means of a group and for rendering the individual builder motion for said group inoperative when the packages on the spindles of that group have reached a predetermined size without affecting the continued building of the remaining packages on the machine. 10
19. An improved doubling and twisting machine, comprising a plurality of swing spindles, means individual to each spindle for swinging it into a non-driving position, a ring rail, means for reciprocating the ring rail vertically with respect to the swing spindles, means for interconnecting the spindle swinging means into a plurality of independently operable groups with a plurality of spindle swinging means in each group, means for interconnecting the spinner rings into a plurality of independently operable groups with the same number of spinner rings in a group as there are spindle swinging means in a group and with the groupings of rings and spindle swinging means coinciding, an auxiliary builder motion individual to each group of rings carried by the ring rail, and means for causing operation of all of the 15
20. An improved doubling and twisting machine, comprising a plurality of swing spindles, a group of single end thread guides for each spindle, means individual to each spindle for swinging it into a non-driving position, means for interconnecting the spindle swinging means into a plurality of independently operable groups with a plurality of the spindle swinging means in each group, and means for causing operation of all of the spindle swinging means of a group when the packages on the spindles of that group have reached a predetermined size without affecting the continued building of the remaining packages on the machine. 20
21. An improved doubling and twisting machine, comprising a plurality of swing spindles, a group of single end thread guides for each spindle, means individual to each spindle for swinging it into a non-driving position, means for interconnecting the spindle swinging means into a plurality of independently operable groups with a plurality of the spindle swinging means in each group, and means for causing operation of all of the spindle swinging means of a group when the packages on the spindles of that group have reached a predetermined size without affecting the continued building of the remaining packages on the machine, said last mentioned means being operable without contacting the yarn of the packages which have been completed. 25
